(57) **ABSTRACT**

A liquid consumption device has a tank having an inner space partitioned by an outer wall. The tank has a first inner wall which extends from the outer wall on a one side in a first direction perpendicular to an up-down direction. Further, the first inner wall partitions the inner space into a first space and a second space, which communicate with each other through a first communication hole formed on the first inner wall. A third space, which is partitioned by the first inner wall and the outer wall, and is located below a lowermost position of a surface defining the first communication hole when the tank takes a first attitude is configured to store a particular amount of liquid, which is stored in a fourth space in a state where the tank takes the usage attitude, the fourth space being a part of the second space.

LIQUID CONSUMPTION DEVICE

CROSS-REFERENCE TO RELATED APPLICATIONS

This application claims priority under 35 U.S.C. § 119 from Japanese Patent Application No. 2017-073264 filed on Mar. 31, 2017. The entire subject matter of the application is incorporated herein by reference.

BACKGROUND

Technical Field

The present disclosures relate to a liquid consumption device having a tank for storing liquid.

Related Art

Conventionally, there has been known an image recording apparatus, which is provided with a tank containing a large-capacity ink storage chamber. Such a tank has an ink inlet from which ink is injected in the storage chamber from outside, and an openable/closable cap member for the inlet. Such an image recording apparatus has an openable cover provided to a casing thereof such that, when the cover is opened, the cap member is exposed to outside. When the cap member is removed with the cover being opened, a user can inject the ink into the storage chamber of the tank through the inlet.

SUMMARY

According to the above-described image recording apparatus, it is possible for a user to close the cover with the cap member being removed. Once the cover is closed, the user cannot visually recognize whether or not the cap member is attached to the inlet. Therefore, it may occur that the image recording apparatus is moved with the cap member being removed. In such a case, if the image recording apparatus is inclined, the ink inside the tank may be spilled out through the inlet of the image recording apparatus. As a result, the cloths of the user and/or a floor may be soiled by the ink. When the image recording apparatus is being carried in such a state with other baggage, the baggage may also be soiled by the ink.

According to aspects of the present disclosures, there is provided a liquid consumption device, having a tank having an inner space partitioned, by an outer wall, from outside, an inlet through which the inner space communicates with the outside of the tank, and an outlet through which the inner space communicates with the outside of the tank, and a liquid consumption part connected to the outlet. The tank has a first inner wall which extends, in a state where the tank takes a usage attitude, from the outer wall on a one side in a first direction perpendicular to an up-down direction. Further, the first inner wall partitions the inner space into a first space in which the inlet is located and a second space in which the outlet is located, the first inner wall having a first communication hole through which the first space and second space communicate with each other. Furthermore, a third space, which is partitioned by the first inner wall and the outer wall and is located below a lowermost position of a surface partitioning the first communication hole when the tank takes a first attitude which is defined as an attitude when the tank taking the usage attitude is rotated on another side in the first direction by an angle ranging from 0 degree to 90

2

degrees about a rotation axis extending in a second direction which is perpendicular to both the up-down direction and the first direction, is configured to store a particular amount of liquid, which is stored in a fourth space in a state where the tank takes the usage attitude, the fourth space being a part of the second space.

BRIEF DESCRIPTION OF THE ACCOMPANYING DRAWINGS

10 FIG. 1 is a cross-sectional view schematically illustrating an internal structure of a printer according to a first embodiment of the present disclosures.

15 FIG. 2 is a plan view showing an arrangement of a carriage and an ink supplying device of the printer.

FIG. 3A is a perspective view of an ink tank according to the first embodiment viewed from upper left side thereof.

FIG. 3B is a cross-sectional view of the ink tank viewed along line MA-MA in FIG. 3A.

20 FIG. 4A is a vertical cross-sectional view of the ink tank according to the first embodiment when the ink tank takes a usage attitude.

FIG. 4B is a vertical cross-sectional view of the ink tank according to the first embodiment when the ink tank takes a first attitude.

FIG. 5A is a vertical cross-sectional view of the ink tank according to the first embodiment when the ink tank takes the usage attitude.

FIG. 5B is a vertical cross-sectional view of the ink tank according to the first embodiment when the ink tank takes a fourth attitude.

FIG. 6 is a vertical cross-sectional view of an ink tank according to a second embodiment when the ink tank takes the usage attitude.

35 FIG. 7A is a vertical cross-sectional view of the ink tank according to the second embodiment when the ink tank takes the usage attitude.

FIG. 7B is a vertical cross-sectional view of the ink tank according to the second embodiment when the ink tank takes the first attitude.

FIG. 7C is a vertical cross-sectional view of the ink tank according to the second embodiment when the ink tank takes a second attitude.

40 FIG. 8A is a vertical cross-sectional view of the ink tank according to the second embodiment when the ink tank takes the usage attitude.

FIG. 8B is a vertical cross-sectional view of the ink tank according to the second embodiment when the ink tank takes the fourth attitude.

FIG. 8C is a vertical cross-sectional view of the ink tank according to the second embodiment when the ink tank takes a fifth attitude.

FIG. 9A is a vertical cross-sectional view of the ink tank according to a third embodiment when the ink tank takes the usage attitude.

FIG. 9B is a vertical cross-sectional view of the ink tank according to the third embodiment when the ink tank takes the fourth attitude.

FIG. 10 is a vertical cross-sectional view of the ink tank according to a fourth embodiment when the ink tank takes the usage attitude.

FIG. 11A is a vertical cross-sectional view of the ink tank according to a fifth embodiment when the ink tank takes the usage attitude.

FIG. 11B is a vertical cross-sectional view of the ink tank according to the fifth embodiment when the ink tank takes the first attitude.

FIG. 11C is a vertical cross-sectional view of the ink tank according to the fifth embodiment when the ink tank takes the second attitude.

FIG. 11D is a vertical cross-sectional view of the ink tank according to the fifth embodiment when the ink tank takes a third attitude.

FIG. 12A is a vertical cross-sectional view of the ink tank according to the fifth embodiment when the ink tank takes the usage attitude.

FIG. 12B is a vertical cross-sectional view of the ink tank according to the fifth embodiment when the ink tank takes the fourth attitude.

FIG. 12C is a vertical cross-sectional view of the ink tank according to the fifth embodiment when the ink tank takes the fifth attitude.

FIG. 12D is a vertical cross-sectional view of the ink tank according to the fifth embodiment when the ink tank takes a sixth attitude.

FIG. 13A is a vertical cross-sectional view of the ink tank according to a sixth embodiment when the ink tank takes the usage attitude.

FIG. 13B is a vertical cross-sectional view of the ink tank according to a seventh embodiment when the ink tank takes the usage attitude.

FIG. 14 is a vertical cross-sectional view of the ink tank according to an eighth embodiment when the ink tank takes the usage attitude.

FIG. 15A is a vertical cross-sectional view of the ink tank according to the eighth embodiment when the ink tank takes the usage attitude.

FIG. 15B is a vertical cross-sectional view of the ink tank according to the eighth embodiment when the ink tank takes the fourth attitude.

FIG. 15C is a vertical cross-sectional view of the ink tank according to the eighth embodiment when the ink tank takes the fifth attitude.

FIG. 15D is a vertical cross-sectional view of the ink tank according to the eighth embodiment when the ink tank takes the sixth attitude.

FIG. 16 is a vertical cross-sectional view of the ink tank according to a ninth embodiment when the ink tank takes the usage attitude.

FIG. 17A is a vertical cross-sectional view of the ink tank according to the ninth embodiment when the ink tank takes the usage attitude.

FIG. 17B is a vertical cross-sectional view of the ink tank according to the ninth embodiment when the ink tank takes the fourth attitude.

FIG. 17C is a vertical cross-sectional view of the ink tank according to the ninth embodiment when the ink tank takes the fifth attitude.

FIG. 17D is a vertical cross-sectional view of the ink tank according to the ninth embodiment when the ink tank takes the sixth attitude.

FIG. 18 is a vertical cross-sectional view of the ink tank according to a tenth embodiment when the ink tank takes the usage attitude.

FIG. 19 is a vertical cross-sectional view of the ink tank according to an eleventh embodiment when the ink tank takes the usage attitude.

FIG. 20 is a vertical cross-sectional view of the ink tank according to a twelfth embodiment when the ink tank takes the usage attitude.

FIG. 21A is a vertical cross-sectional view of the ink tank according to the twelfth embodiment when the ink tank takes the usage attitude.

FIG. 21B is a vertical cross-sectional view of the ink tank according to the twelfth embodiment when the ink tank takes the first attitude.

FIG. 21C is a vertical cross-sectional view of the ink tank according to the ninth embodiment when the ink tank takes the second attitude.

FIG. 21D is a vertical cross-sectional view of the ink tank according to the ninth embodiment when the ink tank takes the third attitude.

10 FIG. 22A is a vertical cross-sectional view of the ink tank according to the twelfth embodiment when the ink tank takes the usage attitude.

FIG. 22B is a vertical cross-sectional view of the ink tank according to the twelfth embodiment when the ink tank takes the fourth attitude.

15 FIG. 22C is a vertical cross-sectional view of the ink tank according to the twelfth embodiment when the ink tank takes the fifth attitude.

FIG. 22D is a vertical cross-sectional view of the ink tank according to the twelfth embodiment when the ink tank takes the sixth attitude.

20 FIG. 23 is a vertical cross-sectional view of the ink tank according to a thirteenth embodiment when the ink tank takes the usage attitude.

25 FIG. 24A is a vertical cross-sectional view of the ink tank according to the thirteenth embodiment when the ink tank takes the usage attitude.

FIG. 24B is a vertical cross-sectional view of the ink tank according to the thirteenth embodiment when the ink tank takes the first attitude.

30 FIG. 24C is a vertical cross-sectional view of the ink tank according to the thirteenth embodiment when the ink tank takes the second attitude.

FIG. 24D is a vertical cross-sectional view of the ink tank according to the thirteenth embodiment when the ink tank takes the third attitude.

35 FIG. 25A is a vertical cross-sectional view of the ink tank according to the thirteenth embodiment when the ink tank takes the usage attitude.

40 FIG. 25B is a vertical cross-sectional view of the ink tank according to the thirteenth embodiment when the ink tank takes the fourth attitude.

FIG. 25C is a vertical cross-sectional view of the ink tank according to the thirteenth embodiment when the ink tank takes the fifth attitude.

45 FIG. 25D is a vertical cross-sectional view of the ink tank according to the thirteenth embodiment when the ink tank takes the sixth attitude.

DETAILED DESCRIPTION OF THE EMBODIMENTS

Hereinafter, referring to the accompanying drawings, embodiments according to the present disclosures will be 55 described. It should be noted that embodiments described below are only examples according to aspects of the present disclosures, and configurations thereof can be modified in various ways without departing from the aspects of the present disclosures.

60 In the following description, an up-down direction 7 is defined based on an attitude of a printer 10 and an ink tank 201 placed for use on a horizontal plane (i.e., the attitude shown in FIG. 1: which will occasionally be referred to as a usage attitude). Further, a direction in which a carriage 38 65 reciprocally moves is referred to as a main scanning direction, which is also defined as a front-rear direction 8. A direction perpendicular to the front-rear direction 8 and the

up-down direction is defined as a right-left direction 8. In particular, according to the embodiments described herein-after, when the printer 10 and the ink tank 201 are in use (i.e., they are in the usage attitude), the up-down direction 7 corresponds to the vertical direction, and the front-rear direction 8 and the right-left direction 9 correspond to the horizontal direction.

[Printer According to First Embodiment]

Firstly, the printer 10 according to a first embodiment of the present disclosures will be described.

[Entire Configuration of Printer]

As shown in FIG. 1, the printer 10 (which is an example of a liquid consumption device) is an image recording apparatus configured to form an image on a sheet 12 in accordance with a so-called inkjet printing method. The printer 10 has a sheet supplier 15, a sheet feed tray 20, a discharge tray 21, a first conveyer 22, a second conveyer 23, a recording assembly 24, a platen 42 and an ink supplier 33. The printer 10 may be configured to have various functions, in addition to a printing function, such as a facsimile function, a scanner function and the like.

[Sheet Feed Tray and Discharge Tray]

The sheet feed tray 20 is arranged at a lower part of the printer 10, and detachably attached to a housing of the printer 10. The sheet feed tray 20 can be detached from or inserted into the housing by sliding the same in the right-left direction 8. The sheet feed tray 20 is configured to support a plurality of sheets 12 in a stacked manner. The discharge tray 21 is formed integrally with the sheet feed tray 20 and is arranged on an upper side with respect to the sheet feed tray 20. Thus, the discharge tray 21 is detached from or attached to the housing of the printer together with (i.e., integrally with) the sheet feed tray 20. The discharge tray 21 receives and supports the sheets 12 conveyed by the second conveyer 23 and discharged from between the recording assembly 24 and the platen 42.

[Sheet Supplier]

As shown in FIG. 1, the sheet supplier 15 includes a feeding roller 25, a feeding arm 26 and a shaft 27. The sheet supplier 15 feeds the sheets 12 supported by the sheet feed tray 20 toward a conveying passage 13. The feeding roller 25 is rotatably supported at a tip end part of the feeding arm 26. The feeding roller 25 is driven to rotate in a forward direction (i.e., counterclockwise in FIG. 1) by a not-shown motor when the sheets 12 is fed. The feeding arm 26 is rotatably supported by the shaft 27 which is supported by a frame of the printer 10. The feeding arm 26 is rotationally urged toward the sheet feed tray 20 (i.e., urged clockwise) by its deadweight or an elastic force generated, for example, by a spring.

It is noted that, when the feeding roller 25 is rotated forwardly, the feeding roller 25 is rotated to feed the sheets 12 in a conveying direction 16. According to the present disclosure, therefore, the forward rotation of the feeding roller 25 is the counterclockwise rotation in FIG. 1. In the following description, regarding not only the feeding roller 25, but the other rollers, the term "forward rotation" means the rotation for feeding the sheets 12 in the conveying direction 16.

[Conveying Passage]

As shown in FIG. 1, the conveying passage 13, which extends upward from the right end part of the sheet feed tray 20, is curved to make a U-turn frontward, and reaches the discharge tray 12 passing through a space between the recording assembly 24 and the platen 42. The printer 10 includes an outer guide member 18 and an inner guide member 19. A curved portion (i.e., a portion making the

U-turn) of the conveying passage 13 is formed by an inside space between the outer guide member 18 and the inner guide member 19. A portion of the conveying passage 13 between the first conveyer 22 and the second conveyer 23 is located at a substantially central part, in the front-rear direction 8, of the printer 10 and extends in the right-left direction 9. Conveying directions of the sheet 12 is indicated by arrows 16 depicted in FIG. 1.

[First Conveyer and Second Conveyer]

10 As shown in FIG. 1, the first conveyer 22 is arranged on an upstream side, in the conveying direction 16, with respect to the recording assembly 24. The first conveyer 22 has a conveying roller 31 and a pinch roller 32 which face each other. The conveying roller 31 is arranged above the pinch roller 32. 15 The sheet 12 conveyed through the curved portion of the conveying passage 13 is nipped by the conveying roller 31 and the pinch roller 32. The conveying roller 31 is driven to rotate by a not-shown motor. The pinch roller 32 is rotated in association with rotation of the conveying roller 31. 20 The sheet 12 nipped by the conveying roller 31 and the pinch roller 32 is conveyed in the conveying direction 16 as the conveying roller 31 and the pinch roller 32 rotate forwardly.

The second conveyer 23 is arranged on a downstream side, in the conveying direction 16, with respect to the recording assembly 24. The second conveyer 23 has a discharging roller 34 and a spur roller 35 face each other. The spur roller 35 is arranged above the discharging roller 34. 25 The sheet 12 conveyed from between the recording assembly 24 and the platen 42 is nipped by the discharging roller 34 and the spur roller 35. The discharging roller 34 is driven to rotate by a not-shown motor. The spur roller 35 is rotated in association with rotation of the discharging roller 34. 30 The sheet 12 nipped by the discharging roller 34 and the spur roller 35 is conveyed in the conveying direction 16 as the discharging roller 34 and the spur roller 35 rotate forwardly.

[Platen]

As shown in FIG. 1, the platen 42 is arranged between, in 40 the conveying direction 16, the first conveyer 22 and the second conveyer 23. The recording assembly 24 and the platen 42 are arranged at opposed positions, in the up-down direction, with the conveying passage 13 sandwiched therebetween. The recording assembly 24 is arranged at a higher 45 position than the platen 42 is. The platen 42 is arranged below the recording assembly 24 and defines a lower surface of the conveying passage 13.

[Recording Assembly]

As shown in FIG. 1, the recording assembly 24 (which is 50 an example of a liquid consumption part) is arranged between, in the conveying direction 16, the first conveyer 22 and the second conveyer 23. The recording assembly 24 has a carriage 38 and a recording head 39.

As shown in FIG. 2, the carriage 38 is supported by guide 55 rails 43 and 44 which extend in the front-rear direction 8 and spaced from each other in the right-left direction 9. The guide rails 43 and 44 are supported by the frame of the printer 10. The carriage 38 is connected to a well-known belt mechanism provided to the guide rail 44. When the belt 60 mechanism 44 is driven by a not-shown motor, the carriage 38 connected to the belt mechanism is driven to reciprocally move in the front-rear direction 8.

As shown in FIG. 1, the carriage 38 mounts the recording head 39. On a lower surface of the recording head 39, a 65 plurality of nozzles 40 is arranged. Tip ends of the plurality of nozzles 40 are exposed to outside from the lower surface of the recording head 39. The plurality of nozzles 40 is

arranged on the downstream side, in the conveying direction, with respect to the conveying roller 31 and the pinch roller 32. The recording head 39 ejects the ink through the plurality nozzles 40 as minute ink droplets. During movement of the carriage 38, the recording head 39 ejects the ink droplets toward the sheet 12 supported on the platen 42, thereby an image being formed on the sheet 12.

[Ink Supplier]

As shown in FIG. 2, the ink supplier 33 has four ink tanks 201. The four ink tanks 201 store four different color ink, respectively. According to the illustrative embodiments, the four ink tanks 201 store black ink, yellow ink, cyan ink and magenta ink, respectively. The ink supplier 33 is configured to supply the ink to the recording assembly 24.

As shown in FIG. 2, the printer 10 has four ink tubes 28 which connect the ink supplier 33 with the recording head 39, and a flexible flat cable 29 which electrically connects a control substrate with the recording head 39. The four ink tubes 28 respectively supply the ink stored in the four ink tanks 201 of the ink supplier 33 to the recording head 39. The four ink tubes 28 are connected to the recording head 39 with being bundled. The flexible flat cable 29 transmits control signals output by the control substrate to the recording head 39.

[Ink Tank According to First Embodiment]

FIG. 3A shows an appearance of the ink tank 201 (which is an example of a tank) according to the first embodiment. As shown in FIG. 3A, the ink tank 201 has a substantially rectangular parallelepiped shape. The ink tank 201 has, in a state where the tank 201 takes a usage attitude, a front outer wall 51, a rear outer wall 52, an upper outer wall 53, a lower outer wall 54, a right outer wall 55 and a left outer wall 56. Each of the front outer wall 51 and the rear outer wall 52 is plate-like part perpendicular to the front-rear direction 8. The rear outer wall 51 is arranged on the rear side with respect to the front outer wall 51. Each of the upper outer wall 53 and the lower outer wall 54 is a plate-like part perpendicular to the up-down direction 7. The lower outer wall 54 is arranged below the upper outer wall 53. Each of the right outer wall 55 and the left outer wall 56 is a plate-like part perpendicular to the right-left direction 9. The left outer wall 56 is arranged on the left side with respect to the right outer wall 55.

The outer walls 51-56 are connected next to each other to form the substantially rectangular parallelepiped shape. When viewed along the up-down direction 7, the upper end sides of the front outer wall 51, the rear outer wall 52, the right outer wall 54 and the left outer wall 55 are connected to outer sides of the upper outer wall 53, and the lower end sides of the front outer wall 51, the rear outer wall 52, the right outer wall 54 and the left outer wall 55 are connected to outer sides of the lower outer wall 54. When viewed along the front-rear direction 8, the front end sides of the upper outer wall 53, the lower outer wall 54, the right outer wall 55 and the left outer wall 56 are connected to the outer sides of the front outer wall 51, and the rear sides of the upper outer wall 53, the lower outer wall 54, the right outer wall 55 and the left outer wall 56 are connected to the outer sides of the rear outer wall 52.

It is noted that the right-left direction 9 is an example of a first direction, and the front-rear direction 8 is an example of the second direction. The right direction is an example of one direction along the first direction, while the left direction is an example of the other direction along the first direction.

As shown in FIG. 3B, the outer walls 51-56 partitions an inner space 57 of the ink tank 201 from the outside. The ink tank 201 has an inlet 5, an outlet 59 and a not-shown air

communicating port, through which the inner space 57 communicates with the outside. According to the present embodiment, the inlet 58 is a through hole piercing the upper outer wall 53 in the up-down direction 7. The inlet 58 is arranged, in the right-left direction 9, on the left side with respect a center of the upper outer wall 53. The outlet 59 is a through hole piercing the right outer wall 55 in the right-left direction 9. The outlet 59 is arranged at a lower end part, in the up-down direction 7, of the right outer wall 55. The air communicating port is a through hole piercing the upper outer wall 53 in the up-down direction.

As shown in FIG. 3A, the ink tank 201 has a cap 49 which is detachably attached to the inlet 58. When the user uses the printer 10, the inlet 58 of the ink tank 201 is normally sealed with the cap 49. When remaining ink 60 inside the ink tank 201 becomes reduced, the user removes the cap 49 from the inlet 58 and inject the ink 60 inside the ink tank 201 through the inlet 58. Thereafter, the user attaches the cap 49 to the inlet 58 to seal the same again. Incidentally, the outlet 59 is connected to the recording head 39 through the ink tubes (see FIG. 2). When the recording head 39 is not driven, the ink 60 inside the ink tank 201 does not flow toward the ink tubes 28 through the outlet 59.

According to the present embodiment, the outer walls 51-56 are molded from resin material and have substantially the same thicknesses. The ink tank 201 is configured such that at least one of the front outer wall 51 and the rear outer wall 52 is adhered to the other outer walls. At least one of the front outer wall 51 and the rear outer wall 52 may be a film formed from the resin material to have a thin-film shape.

As shown in FIG. 3B, the ink tank 201 has a first inner wall 61 which extends, in a state where the ink tank 201 takes the usage attitude, rightward from the left outer wall 51. The first inner wall 61 is a plate-like part substantially perpendicular to the up-down direction 7. The first inner wall 61 connects the front outer wall 51 and the rear outer wall 52. According to the present embodiment, the first inner wall 61 is molded, from the resin material, integrally with the outer walls 51-56, and has substantially the same thickness with each of the outer walls 51-56.

The first inner wall 61 partitions the inner space 57 into two spaces aligned in the up-down direction 7, which are a first space 101 and a second space 102. The first space 101 is a space in which the inlet 58 is arranged. The second space 102 is a space where the outlet 59 is arranged. The first inner wall 61 is formed with a first communication hole 71 through which the first space 101 and the second space 102 communicate with each other. According to the first embodiment, the first communicating hole 71 is provided between the first inner wall 61 and the right outer wall 55. In a state where the ink tank 201 takes the usage attitude, the first inner wall 61 may be configured to extend, in the right-left direction 9, from the left outer wall 56 to the right outer wall 55. In such a case, the first communication hole 71 may be located at an intermediate position of the first inner wall 61 extending from the left outer wall 56 to the right outer wall 55.

As shown in FIG. 3A, on each of the outer walls 51, 52, 55 and 56, a full level line L0 is indicated. The full level line L0 is indicated at a lower position, in a state where the ink tank 201 takes the usage attitude, with respect to the first inner wall 61, and indicates the maximum amount (an example of a maximum liquid amount) of the ink 60 (an example of liquid) storable in the second space 102. If the ink 60 exceeding the maximum amount is stored in the ink tank 201, the printer 10 may not normally operate when the

user uses the printer 10, or other defects such as leakage of the ink, overflow of the ink or the like may tend occur easily. Therefore, a manufacturer of the printer 10 determines, in advance, the maximum amount of the ink 60 storable in the ink tank 201 in a state where the ink tank 201 takes the usage attitude. The full level line L0 is indicated at a position corresponding to an upper surface of the link 60 when the stored amount of the ink 60 takes the usage attitude is the maximum amount. In the second space 102, a space below the full level line L0 is a fourth space 104. Further, on the left outer wall 56, a marking 48 corresponding to the full level line L0 is formed.

[Ink Leakage Preventing Structure]

The ink tank 201 has an ink leakage preventing structure. That is, the ink tank 201 has a particular structure with which, even if the ink tank 201 is inclined about an axis extending along the front-rear direction 8 with the inlet 58 being opened (i.e., the cap 49 being removed from the inlet 58), the ink 60 stored in the inner space 57 is prevented from leaked outside. For example, in a case where the printer 10 is packed for carriage with the ink 60 being stored in the ink tank 201, there could be a chance that the printer 10 is inclined. The ink leakage preventing structure is for preventing the leakage of the ink 60 from the ink tank 201 in such a case. In the following description, as attitudes of the ink tank 201 which is inclined leftward (or rotated counterclockwise) about the axis extending in the right-left direction 8, a first attitude, a second attitude and a third attitude will be referred to. Further, as attitudes of the ink tank 201 inclined rightward (or rotated clockwise) about the axis extending in the right-left direction 8, a fourth attitude, a fifth attitude and a sixth attitude will be referred to.

[First Attitude According to First Embodiment]

Referring to FIGS. 4A and 4B, the ink tank 201 of which attitude is changed from the usage attitude to the first attitude will be described. In a state where the ink tank 201 takes the usage attitude, as shown in FIG. 4A, the ink 60 is stored to the full level line L0 in the inner space 57 of the of the ink tank 201.

FIG. 4B shows the ink tank 201 taking the first attitude. The first attitude is defined as an attitude when the ink tank 201 taking the usage attitude is rotated leftward (i.e., rotated counterclockwise in FIG. 4A) about the axis extending in the front-rear direction 8 such that a rotation angle is larger than 0 degree to 90 degrees or less. Hereinafter, a term "rotation angle" is used to indicate a rotated angle of the ink tank with respect to its usage attitude. That is, in the following description, the rotation angle of "0" degree corresponds to the usage attitude of the ink tank 201, and rotation angles referred to in the following description are angles measured with respect to the usage attitude of the ink tank 201. In the ink tank 201 taking the first attitude as shown in FIG. 4B, a part of the second space 102 serves also as a third space 103. As shown in FIG. 4B, the third space 103 is partitioned by the first inner wall 61, the lower outer wall 54, the left outer wall 56, the front outer wall 51 and the rear outer wall 52. The third space 103 is below a lowest position L1 of a surface of the first inner wall 61 defining the first communication hole 71. The third space 103 is capable of storing the ink 60, which is stored in the fourth space 104 (see FIG. 4A) in a state where the ink tank 201 takes the usage attitude. In other words, in a state where the ink tank 201 takes the first attitude, the first inner wall 61 extends upward such that a capacity of the third space 103 is equal to or larger than the capacity of the fourth space 104.

[Fourth Attitude According to First Embodiment]

Referring to FIGS. 5A and 5B, the ink tank 201 of which attitude is changed from the usage attitude (i.e., the rotation angle is 0 degree) to the fourth attitude will be described. In 5 a state where the ink tank 201 takes the usage attitude, as shown in FIG. 5A, the ink 60 is stored to the full level line L0 in the inner space 57 of the of the ink tank 201.

FIG. 5B shows the ink tank 201 taking the fourth attitude (in particular, the rotation angle is 90 degrees). The fourth 10 attitude is defined as an attitude when the ink tank 201 taking the usage attitude (i.e., when the rotation angle is 0 degree) is rotated rightward (i.e., clockwise in FIG. 5A) about the axis extending in the front-rear direction 8 such that the rotation angle is larger than 0 degree to 90 degrees or less. 15 In the ink tank 201 taking the fourth attitude, a part of the inner space 57 is an eleventh space 111. The eleventh space 111 is partitioned by the upper outer wall 53, the lower outer wall 54, the right outer wall 55, the front outer wall 51 and the rear outer wall 52. The eleventh space 111 is defined 20 below a level of the inlet 58. The eleventh space 111 is capable of storing the ink 60, which is stored in the fourth space 104 (see FIG. 5A) in a state where the ink tank 201 takes the usage attitude. In other words, the inlet 108 is provided such that a capacity of the eleventh space 111, in 25 a state where the ink tank 201 takes the fourth attitude, is equal to or larger than the capacity of the fourth space 104.

Effects of First Embodiment

30 With the printer 10 according to the first embodiment, even if the attitude of the ink tank 201 is changed from the usage attitude to the first attitude in which the ink tank 201 is rotated leftward such that the rotation angle is changed from 0 degree to 90 degrees about the axis extending in the 35 front-rear direction 8, the ink 60 stored in the fourth space 104 below the full level line L0 in a state where the ink tank 201 takes the usage attitude can be reserved in the third space 103. Therefore, even if the ink tank 201 is rotated about the axis extending in the front-rear direction 8 with the cap 49 being removed (i.e., the inlet 58 being opened), the 40 ink 60 inside the inner space 57 hardly flow out of the ink tank 201.

Further, even if the attitude of the ink tank 201 is changed from the usage attitude to the fourth attitude in which the ink 45 tank 201 is rotated rightward such that the rotation angle is changed from 0 degree to 90 degrees about the axis extending in the front-rear direction 8, the ink 60 inside the inner space 57 hardly flow out of the ink tank 201 since the capacity of the eleventh space 111 is equal to or larger than 50 the capacity of the fourth space 104.

[Ink Tank According to Second Embodiment]

Referring to FIGS. 6, 7A-7C and 8A-8C, an ink tank 202 according to a second embodiment of the present disclosures will be described. The ink tank 202 according to the second embodiment has a second inner wall 62 in addition to the structure of the ink tank 201 according to the first embodiment. Since the structure of the ink tank 202 other than the second inner wall 62 is the same as that of the ink tank 201 according to the first embodiment, detail description of the 55 same structure will be omitted.

As shown in FIG. 6, the ink tank 202 has the second inner wall 62 which extends, in a state where the ink tank 202 takes the usage attitude, downward from a part of the first inner wall 61 at a position on the left side with respect to the 60 first communication hole 71. The second inner wall 62 is plate-shaped part perpendicular to the right-left direction 9. The second inner wall 62 connects the front outer wall 51

11

and the rear outer wall 52. According to the present embodiment, the second inner wall 62 is formed integrally with the outer walls 51-56 by molding from the resin, and the thickness of the second inner wall 62 is substantially the same as the thicknesses of the outer walls 51-56.

[First and Second Attitudes According to Second Embodiment]

Referring to FIGS. 7A-7C, the ink tank 200 of which attitude is changed from the usage attitude to a second attitude via a first attitude (i.e., when the rotation angle is changed from 0 degree to 180 degrees) will be described. As shown in FIG. 7A, in a state where the ink tank 202 takes the usage attitude, the ink 60 is stored in the inner space 57 to the full level line L0. That is, the ink 60 is fully stored in a state where the ink tank 202 takes the fourth space 104.

FIG. 7B shows a state where the ink tank 202 takes the first attitude. The first attitude is an attitude when the ink tank 202 taking the usage attitude is rotated leftward (i.e., rotated counterclockwise) from 0 degree to 90 degrees or less about the axis extending in the front-rear direction. In a state where the ink tank 202 takes the first attitude, the second space 102 is partitioned to a fifth space 105 above the second inner wall 62, and a sixth space 106 below the second inner wall 62. In a state where ink tank 202 takes the usage attitude, according to the second embodiment, since the second inner wall 62 extends immediately downward, the sixth space 106 is coincides with the third space 103 of the ink tank 201 according to the first embodiment.

The second inner wall 62 has a second communication hole 72 through which the fifth space 105 and the sixth space 106 communicate with each other. According to the second embodiment, the second communication hole 72 is located between the second inner wall 62 and the lower outer wall 54. In a state where the ink tank 202 takes the usage attitude, the second inner wall 62 may be configured to extend, in the up-down direction, from the first inner wall 61 to the lower outer wall 54. In such a case, the second communication hole 72 may be formed at an intermediate position of the second inner wall 62 extending from the first inner wall 61 to the lower outer wall 54.

The ink 60 stored in the fourth space 104 in a state where the ink tank takes the usage attitude (i.e., when the rotation angle is 0 degree) as shown in FIG. 7A is reserved in the sixth space 106 in a state where the ink tank 202 takes the first attitude as shown in FIG. 7B. It is noted that the capacity of the sixth space 106 is larger than the capacity of the fourth space 104.

FIG. 7C shows the ink tank 202 taking the second attitude. The second attitude is defined as an attitude in a state where the ink tank 202 taking the usage attitude is rotated leftward (i.e., when rotated counterclockwise) about the axis extending in the front-rear direction such that the rotation angle is larger than 90 degrees to 180 degrees or less. In a state where the ink tank 202 takes the second attitude, a part of the sixth space 106 serves also as a seventh space 107. The seventh space 107 is partitioned by the first inner wall 61, the second inner wall 62, the left outer wall 56, the front outer wall 51 and the rear outer wall 52. The seventh space 107 is a space below the lowest position L2 of a surface of the second inner wall 62 defining second communication hole 72. The seventh space 107 is capable of reserving the ink 60 which is stored in the fourth space 104 (see FIG. 4A) in a state where the ink tank 202 takes the usage attitude. In a state where the ink tank 202 takes the second attitude, the second inner wall 62 extends upward such that the capacity of the seventh space 107 is equal to or larger than the capacity of the fourth space 104.

12

As shown in FIG. 7C, the ink 60 stored in the sixth space 106 in a state where the ink tank 202 takes the first attitude (see FIG. 7B: when the rotation angle is 0-90 degrees) is reserved in a seventh space 107 in a state where the ink tank 202 takes the second attitude. The capacity of the seventh space 107 is larger than the capacity of the fourth space 104. Therefore, the ink 60 stored in the fourth space 104 in a state where the ink tank takes the usage attitude (see FIG. 7A) is reserved in the seventh space 107 in a state where the ink tank 202 takes the second attitude as shown in FIG. 7C.

[Fourth and Fifth Attitudes According to Second Embodiment]

Referring to FIGS. 8A-8C, the ink tank 202 of which attitude is changed from the usage attitude to the fifth attitude via the fourth attitude will be described. As shown in FIG. 8A, in the inner space 57 of the ink tank 202 taking the usage attitude, the ink 60 is stored up to the full level line L0. That is, the fourth space is filled with the ink 60.

FIG. 8B shows a state where the ink tank 202 takes the fourth attitude. The fourth attitude is defined as an attitude in a state where the ink tank 202 taking the usage attitude is rotated rightward (i.e., clockwise) about the axis extending in the front-rear direction 8 such that the rotation angle is larger than 0 degree to 90 degrees or less. In a state where the ink tank 202 takes the fourth attitude, a part of the inner space 57 is the eleventh space 111 which is described above referring to FIG. 5B. When the attitude of the ink tank 202 is changed from the usage attitude (FIG. 8A) to the fourth attitude (FIG. 8B), the ink 60 stored in the fourth space 104 is reserved in the eleventh space 111.

FIG. 8C shows the ink tank 202 taking the fifth attitude. The fifth attitude is defined as an attitude when the ink tank taking the usage attitude is rotated rightward (i.e., clockwise) about the axis extending in the front-rear direction such that the rotation angle is larger than 90 degrees to 180 degrees or less. It is noted that the fifth attitude is the same as the second attitude described above referring to FIG. 7C.

When the attitude of the ink tank 202 is changed from the fourth attitude shown in FIG. 8B to the fifth attitude shown in FIG. 8C, a part of the ink 60 stored in the eleventh space 111 is reserved in the seventh space 107, and the remainder is stored in the first space 101. The ink stored in the first space 101 could flow outside in a state where the cap 49 is removed from the ink tank 202.

Effects of Second Embodiment

With the printer 10 according to the second embodiment, even when the attitude of the ink tank 202 is changed from the usage attitude to the second attitude which is the attitude when the ink tank 202 is rotated leftward by 90 degrees to 180 degrees about the axis extending in the front-rear direction, the ink 60 stored in the fourth space 104, below the full level line L0 in a state where the ink tank 202 takes the usage attitude is reserved in the seventh space 107. Therefore, even if the ink tank 202 is rotated about the axis extending in the front-rear direction 8 with the inlet 58 being opened, the ink 60 stored in the inner space 57 hardly flows outside.

Further, even when the attitude of the ink tank 202 is changed from the usage attitude to the fifth attitude which is the attitude when the ink tank 202 is rotated rightward by 90 degrees to 180 degrees about the axis extending in the front-rear direction 8, a part of the ink 60 stored in the eleventh space 111 is reserved in the seventh space 107, and the ink 60 stored in the inner space 57 hardly flows outside.

13

[Ink Tank According to Third Embodiment]

Referring to FIG. 9A, an ink tank 203 according to a third embodiment will be described. The ink tank 203 according to the third embodiment is provided with a first inner wall 161 which is different from the first inner wall 61 of the ink tank 101 according to the first embodiment. Since the other structure of the ink tank 203 is the same as that of the ink tank 201, only the first inner wall 161 will be described.

As shown in FIG. 9A, the first inner wall 161 of the ink tank 203 extends in a lower right direction in a state where the ink tank 203 takes the usage attitude. In a state where the ink tank 203 takes the usage attitude, a distance of a portion on an upper surface 161a of the first inner wall 161 from the left outer wall 56 toward the right outer wall 55 is longer, the portion on the upper surface 161a of the first inner wall 161 is located at a lower position.

Effect of Third Embodiment

With the printer 10 according to the third embodiment, since the distance of a portion on an upper surface 161a of the first inner wall 161 from the left outer wall 56 toward the right outer wall 55 is longer, the portion on the upper surface 161a of the first inner wall 161 is located at a lower position, the ink 60 is prevented from being kept collected on the first inner wall 161. Therefore, generation of unusable ink which cannot be used by the recording assembly in a state where the ink tank 203 takes the usage attitude can be prevented in addition with the effect provided by the first embodiment.

[Ink Tank According to Fourth Embodiment]

Referring to FIG. 9B, an ink tank 204 according to a fourth embodiment will be described. The ink tank 204 according to the fourth embodiment is configured such that the first inner wall 161 according to the third embodiment is provided to the ink tank 202 according to the second embodiment, and further a second inner wall 162, which is different from the first inner wall 62 of the second embodiment, is provided. The other configuration of the fourth embodiment is the same as that of the second embodiment and the detail description thereof will be omitted.

As shown in FIG. 9B, in a state where the ink tank 204 takes the first attitude, the inner wall 162 provided to the ink tank 204 extends in a lower right direction such that a right side surface 162a of the second inner wall 162 inclines downward from the first inner wall 161 side toward the right side in a state where the ink tank 204 takes the first attitude. Accordingly, in a state where the ink tank 204 takes the usage attitude, the second inner wall 162 extends in the lower left direction such that the right side surface 162a of the second inner wall 162 extends downward from the first inner wall side 161 toward the left side.

Effects of Fourth Embodiment

With the printer 10 according to the fourth embodiment, since the second inner wall 162 is shifted leftward as it extends downward in a state where the ink tank 204 takes the usage attitude. Therefore, in a state where the ink tank 204 takes the first attitude, the ink 60 is prevented from being collected on the second inner wall 62, and thus, from flowing toward the inlet 58.

[Ink Tank According to Fifth Embodiment]

Referring to FIGS. 10, 11A-11D and 12A-12D, an ink tank 205 according to a fifth embodiment will be described. The ink tank 205 according to the fifth embodiment is configured to have the structure of the ink tank 202 according to the second embodiment, and further a third inner wall

14

63. The other configuration of the ink tank 205 according to the fifth embodiment is the same as that of the second embodiment, and the detailed description therefor will be omitted.

5 As shown in FIG. 10, the ink tank 205 has a third inner wall 63 which extends leftward from a position of the second inner wall 62 on an upper side with respect to the second communication hole 72 in a state where the ink tank 205 takes the usage attitude. The third inner wall 63 is a plate-shaped part extending in the up-down direction 7. The third inner wall 63 connects the front outer wall 51 and the rear outer wall 52. The third inner wall 63 is formed by molding from the resin material integrally with the outer walls 51-56, and the thickness of the third wall 63f is substantially the same as the thicknesses of the outer walls 51-56.

[First, Second and Third Attitude of Fifth Embodiment]

Referring to FIGS. 11A-11D, the ink tank 205 of which attitudes is changed from the usage attitude to the first attitude, from the first attitude to the second attitude, from the second attitude to the third attitude, from the third attitude to the fourth attitude. As shown in FIG. 11A, the ink 60 is stored in the inner space 57 of the ink tank 205, in a state where the ink tank 205 takes the usage attitude, up to the full level line L0. That is, the ink 60 is filled with the fourth space 104.

FIG. 11B shows the ink tank 205 taking the first attitude. The first attitude is an attitude of the ink tank 205 when the 30 ink tank 205 taking the usage attitude is rotated leftward by 90 degrees about the axis extending in the front-rear direction 8. In the ink tank 205 taking the first attitude, the second space 102 is partitioned to the fifth space 105, which is described above referring to FIG. 7B in the second embodiment, and a six space 106. The ink 60 stored in the fourth space 104, in a state where the ink tank 205 takes the fourth space 104, is reserved in the sixth space 106 in a state where the ink tank 205 takes the first attitude shown in FIG. 11B.

FIG. 11C shows the ink tank 205 taking the second attitude. The second attitude is defined as an attitude of the 40 ink tank 205 when the ink tank 205 taking the usage attitude is rotated leftward (i.e., counterclockwise) about the axis extending in the front-rear direction 8 such that the rotation angle is larger than 90 degrees to 180 degrees or less. In the 45 ink tank 205 taking the second attitude, the sixth space 106 is partitioned to an eighth space 108 located on an upper side with respect to the third inner wall 63 and a ninth space 109 located on a lower side with respect to the third inner wall 63.

The third inner wall 63 has a third communication hole 73 through which the eighth space 108 and the ninth space 109 communicate with each other. According to the fifth embodiment, the third communication hole 73 is formed between the third inner wall 63 and the left outer wall 56. In a state where the ink tank 205 takes the usage attitude, the third inner wall 63 may extend, in the right-left direction, from the second inner wall 62 to the left outer wall 56. In this case, the third communication hole 73 is formed at an intermediate position of the third inner wall 63 extending from the second inner wall 62 to the left outer wall 56.

As shown in FIG. 11C, the ink 60 stored in the sixth space 106 in a state where the tank 205 takes the first attitude as shown in FIG. 11B is reserved in the ninth space 109 in a state where the ink tank 205 takes the second attitude. The 65 capacity of the ninth space 109 is equal to or larger than the capacity of the fourth space 104. Therefore, the ink 60 reserved in the fourth space 104 in a state where the ink tank

15

205 takes the usage attitude as shown in FIG. 11A is reserved in the ninth space 109 in a state where the ink tank 205 takes the second attitude.

FIG. 11D shows the ink tank 205 taking the third attitude. The third attitude is an attitude of the ink tank 205 when the ink tank 205 taking the usage attitude is rotated leftward by 270 degrees about the axis extending in the front-rear direction 8. In the ink tank 205 taking the third attitude, a part of the ninth space 109 is a tenth space 110. The tenth space 110 is partitioned by the first inner wall 61, the second inner wall 62, the third inner wall 63, the front outer wall 51 and the rear outer wall 52. The tenth space 110 is defined on the lower side with respect to a lowermost position L3 of a surface of the third inner wall 63 defining the third communication hole 73. The tenth space 110 can store the ink 60 stored in the fourth space 104 (see FIG. 4A) of the ink tank 205 taking the usage attitude. In a state where the ink tank 205 takes the third attitude, the third inner wall 63 extends upward such that the capacity of the tenth space 110 is equal to or larger than the capacity of the fourth space 104.

As shown in FIG. 11D, the ink 60 stored in the ninth space 109 of the ink tank 205 taking the second attitude as shown in FIG. 11C is reserved in the tenth space 110 in a state where the ink tank 205 takes the third attitude. The capacity of the tenth space 110 is equal to or larger than the capacity of the fourth space 104. Therefore, the ink 60 stored in the fourth space 104 of the ink tank 205 taking the usage attitude as shown in FIG. 11A is reserved in the tenth space 110 in a state where the ink tank 205 takes the third attitude.

When the ink tank 205 is rotated leftward about the axis in the front-rear direction 8 to change the attitude of the ink tank 205 from the third attitude to the usage attitude, the ink 60 stored in the tenth space 110 is reserved in the fourth space 104.

[Fourth, Fifth and Sixth Attitudes According to Fifth Embodiment]

Referring to FIGS. 12A-12D, the ink tank 205 of which attitude is changed from the usage attitude to the fourth attitude, from the fourth attitude to the fifth attitude, from the fifth attitude to the sixth attitude will be described. As shown in FIG. 12A, the ink 60 is stored in the inner space 57 of the ink tank 205 taking the usage attitude up to the full level line L0.

FIG. 12B shows the ink tank 205 taking the fourth attitude. The fourth attitude is defined as an attitude of the ink tank 205 when the ink tank 205 taking the usage attitude is rotated rightward (i.e., clockwise) about the axis extending in the front-rear direction 8 such that the rotation angle is larger than 0 degree to 90 degrees or less. The fourth attitude coincides with the third attitude which is described above referring to FIG. 11D.

When the attitude of the ink tank 205 is changed from the usage attitude shown in FIG. 12A to the fourth attitude shown in FIG. 12B, a part of the ink 60 stored in the fourth space 104 is reserved in the tenth space 110, while the remainder is reserved in the fifth space 105.

FIG. 12C shows the ink tank 205 taking fifth attitude. The fifth attitude is defined as an attitude of the ink tank 205 when the ink tank 205 taking the usage attitude is rotated rightward (i.e., clockwise) about the axis extending in the front-rear direction 8 such that the rotation angle is larger than 90 degrees to 180 degrees or less. The fifth attitude coincides with the second attitude which is described above referring to FIG. 11C.

When the attitude of the ink tank 205 is changed from the fourth attitude shown in FIG. 12B to the fifth attitude shown in FIG. 12C, the ink 60 stored in the tenth space 110 in FIG.

16

12B is reserved in the ninth space 109 in FIG. 12C, while the ink 60 stored in the fifth space 105 in FIG. 12B is moved to the first space 101 in FIG. 12C. The ink 60 moved to the first space 101 flows outside when the cap 49 is removed from the ink tank 205.

FIG. 12D shows the ink tank 205 taking the sixth attitude. The sixth attitude is defined as an attitude of the ink tank 205 when the ink tank 205 taking the usage attitude is rotated rightward (i.e., clockwise) about the axis extending in the front-rear direction 8 such that the rotation angle is larger than 180 degrees to 270 degrees or less. The sixth attitude coincides with the first attitude described above referring to FIG. 11B.

When the attitude of the ink tank 205 is changed from the fifth attitude shown in FIG. 12C to the sixth attitude shown in FIG. 12D, the ink 60 stored in the ninth space 109 is reserved in the sixth space 106.

When the ink tank 205 taking the sixth attitude is rotated rightward about the axis extending in the front-rear direction 8 so that the attitude of the ink tank 205 is changed from the sixth attitude to the usage attitude, the ink 60 stored in the sixth space 106 is reserved in the fourth space 104.

Effects of Fifth Embodiment

With the printer 10 according to the fifth embodiment, even if the attitude of the ink tank 205 is changed from the usage attitude to the sixth attitude which is defined as an attitude when the ink tank 205 is rotated rightward (i.e., clockwise) about the axis extending in the front-rear direction 8 such that the rotation angle is larger than 180 degrees to 270 degrees or less, a part of the ink 60 stored in the fourth space 104 which is below the full level line L0 in a state where the ink tank 205 takes the usage attitude is reserved in the sixth space 106 in a state where the ink tank 205 takes the sixth attitude. Accordingly, even if the ink tank 205 is rotated about the axis extending in the front-rear direction 8 with the inlet 58 thereof being opened, the ink 60 in the inner space 57 hardly flows out of the ink tank 205.

[Ink Tank According to Sixth Embodiment]

Referring to FIG. 13A, an ink tank 206 according to a sixth embodiment will be described. The ink tank 206 according to the sixth embodiment is configured such that the first inner wall 161 according to the third embodiment and the second inner wall 162 according to the fourth embodiment are provided in the ink tank 205 according to the fifth embodiment, and further a third inner wall 163 different from the third inner wall. The other configuration of the sixth embodiment is the same as that for the fifth embodiment, detailed description thereon will be omitted.

As shown in FIG. 13A, when the ink tank 206 takes the usage attitude, the third inner wall 163 provided to the ink tank 206 extends in a lower right direction, and a lower surface 163a of the third inner wall 163 extends downward as it extends rightward from the second inner wall 162. Accordingly, the third inner wall 163 extends in the upper left direction in a state where the ink tank 206 takes the usage attitude, and the lower surface of the third inner wall 163a extends upward as it extends leftward from the second inner wall 162.

Effects of Sixth Embodiment

With the printer 10 according to the sixth embodiment, since the lower surface 163a of the third inner wall 163 extends upward as the third wall 163 extends upward as it extends leftward, the ink 60 collected on the third inner wall

163 flows toward the ninth space 109 but not toward the inlet 58 in a state where the ink tank 206 takes the second attitude. Therefore, according to the sixth embodiment, it is possible to prevent the ink 60 from flowing out of the inlet 58.

[Ink Tank According to Seventh Embodiment]

Referring to FIG. 13B, an ink tank 207 according to a seventh embodiment will be described. The ink tank 207 according to the seventh embodiment is configured such that, in the ink tank 206 according to the sixth embodiment, the third inner wall 163 of the sixth embodiment is replaced with another third wall 263 which is different from the third wall 163. The other configuration of the seventh embodiment is the same as that of the sixth embodiment, the detailed description thereof will be omitted.

As shown in FIG. 13B, the third inner wall 263 provided to the ink tank 207 extends leftward from the second inner wall 162 in a state where the ink tank 207 takes the usage attitude. A lower surface 263a of the third inner wall 263 extends upward as it extends leftward from the second inner wall 162. Further, an upper surface 273b of the third inner wall 263 extends downward as it extends leftward from the second inner wall 162.

Effects of Seventh Embodiment

With the printer 10 according to the seventh embodiment, in a state where the ink tank 207 takes the usage attitude, the upper surface 273b of the third inner wall 263 extends downward as the third wall 263 extends leftward. Therefore, when the ink tank 207 takes the usage attitude, the ink 60 is prevented from being collected on the third inner wall 263. Accordingly, when the ink tank 207 takes the usage attitude, generation of the ink 60 which cannot be used in the recording assembly 24 can be prevented.

[Ink Tank According to Eighth Embodiment]

Referring to FIGS. 14 and 15A-15D, an ink tank 208 according to an eighth will be described. The ink tank 208 according to the eighth embodiment is configured such that fourth inner walls 64 are provided in addition to the configuration of the ink tank 202 according to the second embodiment. The other configuration of the eighth embodiment is the same as that of the second embodiment, the detailed description thereof will be omitted.

As shown in FIG. 14, the ink tank 208 has four fourth inner walls 64 which extend leftward from the second inner wall 62 in a state where the ink tank takes the usage attitude. The fourth inner walls 64 are located below the first inner wall 61 and above the third inner wall 63. Each of the fourth inner walls 64 is a plate-shaped part extending perpendicular to the up-down direction 7. The fourth inner walls 64 connect the front outer wall 51 and the rear outer wall 52. According to the present embodiment, the fourth inner walls 64 are formed integrally with the outer walls 51-56 by molding from the resin material, and each of the fourth inner walls 64 has the thickness substantially same as the respective thicknesses of the outer walls 51-56.

The fourth inner walls 64 partitions the ninth space 109 into a space on the upside of each fourth inner wall 64 and a space on the downside of each fourth inner wall 64. The ninth space is a space partitioned by the first inner wall 61, the second inner wall 62, the third inner wall 63, the front outer wall 51 and the rear outer wall 52, and is described above, referring to FIG. 11C, in relation to the ink tank 205 according to the fifth embodiment.

Each of the fourth inner walls 64 has a communication hole 74 through which the upside space and the downside space partitioned by each of the fourth inner walls 64

communicate with each other. According to the eighth embodiment, each of the fourth communication holes 74 is formed at a position between each of the fourth inner walls 64 and the left outer wall 56. When the ink tank 208 takes the usage attitude, each of the fourth inner walls 64 may extend, in the right-left direction 9, from the second inner wall 62 to the left outer wall 56. In such a case, the fourth communication holes 74 may be formed at intermediate positions between the second inner wall 62 to the left outer wall 56 of the fourth inner walls 64, respectively.

[Fourth, Fifth and Sixth Attitudes According to Eighth Embodiment]

Referring to FIGS. 15A-15D, the ink tank 208 of which attitude is changed from the usage attitude to a sixth attitude through a fourth attitude and a fifth attitude will be described. As shown in FIG. 15A, in the inner space 57 of the ink tank 208 taking the usage attitude, the ink 60 is stored up to the full level line L0.

FIG. 15B shows the ink tank 208 of which attitude it being changed from the usage attitude to the fourth attitude. The fourth attitude is defined as an attitude of the ink tank 208 when the ink tank 208 taking the usage attitude is rotated rightward (i.e., clockwise) about the axis extending in the front-rear direction 8 such that the rotation angle is larger than 0 degree to 90 degrees or less. Since the ink tank 208 according to the eighth embodiment has the fourth inner walls 64 partitioning the ninth space 109, the ink 60 can be reserved well in the ninth space 109 when the attitude of the ink tank 208 is changed from the usage attitude to the fourth attitude in comparison with the ink tank 205 according to the fifth embodiment described above referring to FIGS. 11A-11D.

A part of the ink 60 stored in the fourth space 104 in a state where the ink tank 208 takes the usage attitude shown in FIG. 15A is stored in the tenth space 110 in a state where the ink tank 208 takes the fourth attitude shown in FIG. 15C, and the remainder of the ink 60 is stored in a space below the second inner wall 62. Further, the ink 60 stored in the tenth space 110 of the ink tank 208 taking the fourth attitude as shown in FIG. 15C is reserved in the ninth space 109 of the ink tank 208 taking the fifth attitude as shown in FIG. 15D.

It is noted that, when the attitude of the ink tank 208 is changed from the usage attitude to the third attitude through the second attitude, the fourth inner walls 64 have little effect in regard with storage of the ink 60, and the ink tank 208 functions substantially the same as the ink tank 205 according to the fifth embodiment.

Effects of Eighth Embodiment

With the printer 10 according to the eighth embodiment, when the ink tank 208 takes the usage attitude, the fourth walls 64 divides the ninth space 109 in the up-down direction 7. Therefore, when the attitude of the ink tank 208 is changed from the usage attitude to the fourth attitude, the liquid is hardly spilled out from the ninth space 109, and the amount of the liquid flowing toward the inlet 58 can be reduced.

[Ink Tank According to Ninth Embodiment]

Referring to FIGS. 16 and 17A-17D, an ink tank 209 according to a ninth embodiment will be described. The ink tank 209 according to the ninth embodiment is configured such that a first inner wall 261, which is different from the first inner wall 61 according to the second embodiment, and a fifth inner wall 65 are provided to the ink tank 202 according to the second embodiment. The other configura-

tion of the fifth embodiment is the same as that of the second embodiment, the detailed description thereof will be omitted.

As shown in FIG. 16, the first inner wall 261 provided to the ink tank 209 extends in the lower right direction from the upper wall 53 in a state where the ink tank 209 takes the usage attitude. An upper end of the first inner wall 261 is located on the left side with respect to the inlet 58.

When the ink tank 209 takes the usage attitude, the fifth inner wall 65 extends in the lower right direction from the upper outer wall 53. An upper end of the fifth inner wall 65 is located on the right side with respect to the inlet 58. The fifth inner wall 65 has an upper part 66 extending downward, and a lower part 67 extending in the lower right direction from the lower end of the upper part 66. Between the first inner wall 261 and the fifth inner wall 65, in the up-down direction 7, a clearance is formed. The clearance allows the ink 60 to flow from the inlet 58 to the fourth space 104.

The fifth inner wall 65 partitions the first space 101 into a twelfth space 112 in which the inlet 58 is located, and a thirteenth space 113 located on the right side with respect to the twelfth space 112 in a state where the ink tank 209 takes the usage attitude.

The fifth inner wall 65 has a fifth communication hole 75 through which the twelfth space 112 and the thirteenth space 113 communicate with each other. According to the ninth embodiment, the fifth communication hole 75 is located between the fifth inner wall 65 and the right outer wall 55. In a state where the ink tank 209 takes the usage attitude, the fifth inner wall 65 may extend in the lower right direction from the upper outer wall 53 to the right outer wall 55. In such a case, the fifth communication hole 75 may be formed at an intermediate position of the fifth inner wall 65 extending from the upper outer wall 53 to the right outer wall 55.

[Fourth and Fifth Attitudes According to Ninth Embodiment]

Referring to FIGS. 17A-17D, the ink tank 209 of which attitude is changed from the usage attitude to the fifth attitude through the fourth attitude will be described. As shown in FIG. 17A, in the inner space 57 of the ink tank 209 taking the usage attitude, the ink 60 is stored up to the full level line L0. That is, the fourth space 104 is filled with the ink 60.

FIG. 17B shows the ink tank 209 taking the fourth attitude. The fourth attitude is defined as an attitude of the ink tank 209 when the ink tank 209 taking the usage attitude is rotated rightward (i.e., clockwise) about the axis extending in the front-rear direction 8 such that the rotation angle is larger than 0 degree to 90 degrees or less. When the attitude of the ink tank 209 is changed from the usage attitude to the fourth attitude, the ink 60 stored in the fourth space 104 is reserved in the eleventh space 111.

FIG. 17C shows the ink tank 209 taking the fifth attitude. The fifth attitude is defined as an attitude of the ink tank 209 when the ink tank 209 taking the usage attitude is rotated rightward (i.e., clockwise) about the axis extending in the front-rear direction 8 such that the rotation angle is larger than 90 degrees to 180 degrees or less. When the ink tank 209 takes the fifth attitude, a fourteenth space 114 is formed in a part of the thirteenth space 113. As shown in FIGS. 16 and 17C, the fourteenth space 114 is partitioned by the fifth inner wall 65, the upper outer wall 53, the right outer wall 55, the front outer wall 51 and the rear outer wall 52, and is defined as a space arranged below a lowermost position L5 of a surface of the fifth inner wall 65 defining the fifth communication hole 75.

When the attitude of the ink tank 209 is changed from the fourth attitude shown in FIG. 17B to the fifth attitude shown in FIG. 17C, a part of the ink 60 stored in the eleventh space 111 is reserved in the seventh space 107, and the remainder flows from the fourth space 104 into the fourteenth space 114 through the fifth space 105. The fourteenth space 114 is configured to reserve all the amount of the ink 60 flows into the fourteenth space 114 when the attitude of the ink tank 209 is changed from the fourth attitude to the fifth attitude.

FIG. 17D shows the ink tank 209 taking the sixth attitude. The sixth attitude is the attitude of the ink tank 209 when the ink tank 209 taking the usage attitude is rotated rightward by 270 degrees about the axis extending in the front-rear direction 8. When the ink tank 209 takes the sixth attitude, a part of the fourteenth space is a fifteenth space 115. As shown in FIGS. 16 and 17D, the fifteenth space 115 is a part of the fourteenth space 114, and is partitioned by the fifth inner wall 65, the upper outer wall 53, the front outer wall 51 and the rear outer wall 52. The fifteenth space 115 is a space defined below the lowermost position L6 of a surface of the fifth inner wall 65 defining the communication hole 75. When the attitude of the ink tank 209 is changed from the fifth attitude shown in FIG. 17C to the sixth attitude shown in FIG. 17D, the ink 60 stored in the fourteenth space 114 is reserved in the fifteenth space 115.

When the attitude of the ink tank 209 is changed from the usage attitude to the third attitude through the second and the third attitudes, the ink tank 209 functions the same as the ink tank 202 according to the second embodiment.

Effects of Ninth Embodiment

With the printer 10 according to the ninth embodiment, since the ink tank 209 has the fifth inner wall 65, even if the ink tank 209 is rotated rightward by degrees about the axis extending in the front-rear direction 8 so that the attitude of the ink tank 209 is changed from the usage attitude to the fifth attitude, part of the ink 60, among the ink stored in the fourth space 104 which is below the full level line L0 in a state where the ink tank 209 takes the usage attitude, split out of the sixth space 106 or the seventh space 107 is reserved in the fourteenth space 114. Therefore, even if the ink tank 209 is rotated about the axis extending in the front-rear direction 8 with the inlet 58 being opened, the ink 60 inside the inner space 57 hardly flows out from the ink tank 209.

Further, even if the ink tank 209 is rotated rightward from 180 to 270 degrees such that the attitude of the ink tank 209 is changed from the fifth attitude to the six attitude, the ink 60 stored in the fourteenth space 114 is reserved in the fifteenth space 115. Therefore, even if the ink tank 209 is rotated about the axis extending in the front-rear direction 8 with the inlet 58 thereof being opened, the ink 60 inside the inner space 57 hardly flows out of the ink tank 209.

Ink Tank According to Tenth Embodiment

Referring to FIG. 18, an ink tank 210 according to a tenth embodiment will be described. The ink tank 210 according to the tenth embodiment is configured such that the third inner wall 263 of the seventh embodiment is provided in the ink tank 209 according to the ninth embodiment. The other configuration of the tenth embodiment is the same as the ninth embodiment and the detailed description thereof will be omitted.

Ink Tank According to Eleventh Embodiment

Referring to FIG. 19, an ink tank 211 according to an eleventh embodiment will be described. The ink tank 211 according to the eleventh embodiment is configured such that the fourth inner wall 64 of the eighth embodiment is

provided in the ink tank 210 according to the tenth embodiment. The other configuration of the eleventh embodiment is the same as the tenth embodiment, and the detailed description thereof will be omitted.

[Ink Tank According to Twelfth Embodiment]

Referring to FIGS. 20 and 21A-21D, an ink tank 212 according to the twelfth embodiment will be described. The ink tank 212 according to the twelfth embodiment is configured such that inner walls 506-510, which are different from the first wall 61 according to the first embodiment, are provided in the ink tank 201 according to the first embodiment. The other configuration of the twelfth embodiment is the same as that of the first embodiment and the description thereof will be omitted.

As shown in FIG. 20, the ink tank 212 has a sixth inner wall 506, a seventh inner wall 508, an eighth inner wall 508, a ninth inner wall 509 and a tenth inner wall 510.

In a state where the ink tank 212 takes the usage attitude, the sixth wall 506 extends in a lower right direction from the upper outer wall 53, and partitions the inner space 57 into a twentieth space 120 in which the inlet 58 is located and a twenty-first space in which the outlet 59 is located. The sixth inner wall 506 has a sixth communication hole 606 through which the twentieth space 120 and the twenty-first space 121 communicate with each other.

In a state where the ink tank 212 takes the usage attitude, the seventh inner wall 507 is arranged below the sixth inner wall 506. Further, the seventh inner wall 507 extends leftward from a portion of the sixth inner wall 506 at a position on the left side with respect to the sixth communication hole 606. The seventh inner wall 507 partitions the twenty-first space 121 into a twenty-second space 122 on the upper side of the seventh inner wall 507 and a twenty-third space 123 on the lower side of the seventh inner wall 507. The seventh inner wall 507 has a seventh communication hole 607 through which the twenty-second space 122 and the twenty-third space 123 communicate with each other.

In a state where the ink tank 212 takes the usage attitude, the eighth inner wall 508 is located on the lower side with respect to the seventh inner wall 507, and extends leftward from the right outer wall 55. The eighth inner wall 508 partitions the twenty-third space 123 into a twenty-fourth space 124 on the upper side of the eighth inner wall 508 and a twenty-fifth space 125 on the lower side of the eighth inner wall 508. The eighth inner wall 508 has an eighth communication hole 608 through which the twenty-fourth space 124 and the twenty-fifth space 125 communicate with each other.

In a state where the ink tank 212 takes the usage attitude, the ninth inner wall 509 extends downward from a portion of the eighth inner wall 508 at a position on the right side with respect to the communication hole 608. The ninth inner wall 509 partitions the twenty-fifth space 125 into a twenty-sixth space 126 on the left side of the ninth inner wall 509 and a twenty-seventh inner wall 127 on the right side of the ninth inner wall 509. The ninth inner wall 509 has a ninth communication hole 609 through which the twenty-sixth space 126 and the twenty-seventh space 127 communicate with each other.

In a state where the ink tank 212 takes the usage attitude, the tenth inner wall 510 extends rightward from a portion of the ninth inner wall 509 at a position on the upper side of the ninth communication hole 609. The tenth inner wall 510 partitions the twenty-seventh space 127 into a twenty-eighth space 128 on the upper side of the tenth inner wall 510 and a twenty-ninth space 129. The tenth inner wall 510 has a

tenth communication hole 610 through which the twenty-eighth space 128 and the twenty-ninth space 129 communicate with each other.

The full level line L0 formed to the ink tank 212 is located on the lower side with respect to the eighth inner wall 508, and indicates the maximum amount of the ink 60 storable in the twenty-fifth space 125. A part of the twenty-fifth space 125 below the full level line L0 is defined as a thirty-second space 132.

[First, Second and Third Attitudes According to Twelfth Embodiment]

Referring to FIGS. 21A-21D, the ink tank 212 of which attitudes is changed from the usages attitude to the third attitude through the first attitude and the second attitude will be described. As shown in FIG. 21A, in the twenty-fifth space 125 of the ink tank 212 taking the usage attitude, the ink 60 is stored up to the full level line L0. That is, the thirty-second space 132 is filled with the ink 60.

FIG. 21B shows the ink tank 212 taking the first attitude. The first attitude is defined as an attitude of the ink tank 212 when the ink tank 212 taking the usage attitude is rotated leftward by 90 degrees about the axis extending in the front-rear direction 8.

In the ink tank 212 taking the first attitude, a thirtieth space 130 and a thirty-first space 131 are included in the inner space 57 as parts thereof. The thirtieth space 130 is partitioned by the eighth inner wall 508, the ninth inner wall 509, the tenth inner wall 510, the front outer wall 51 and the rear outer wall 52. The thirtieth space 130 is located on the lower side with respect to the lowermost position L10 of the surface of the tenth inner wall 51 defining the tenth communication hole 610. The thirty-first space 131 is portioned by the seventh inner wall 507, the left outer wall 56, the lower outer wall 54, the front outer wall 51 and the rear outer wall 52, and is located on the lower side with respect to the lowermost position of the surface partitioning the seventh communication hole 607 of the seventh inner wall 507.

The ink 60 stored in the thirty-second space 132 of the ink tank 212 taking the usage attitude as shown in FIG. 21A is reserved in the thirtieth space 130 and the thirty-first space 131 when the attitude of the ink tank 212 is changed to the first attitude as shown in FIG. 21B.

FIG. 21C shows the ink tank 212 taking the second attitude. The second attitude is defined as an attitude of the ink tank 212 when the ink tank 212 taking the usage attitude is rotated leftward (i.e., counterclockwise) about the axis extending in the front-rear direction 8 such that the rotation angle is larger than 90 degrees to 180 degrees or less. The ink 60 stored in the thirtieth space 130 and the thirty-first space 131 of the ink tank 212 taking the first attitude as shown in FIG. 21B is reserved in the twenty-eighth space 128 and the twenty-second space 122 of the ink tank 212 taking the second attitude as shown in FIG. 21C.

FIG. 21D shows the ink tank 212 taking the third attitude. The third attitude is defined as an attitude of the ink tank 212 when the ink tank 212 taking the usage attitude is rotated leftward (i.e., counter clockwise) about the axis extending in the front-rear direction 8 such that the rotation angle is larger than 180 degrees to 270 degrees or less.

In the ink tank 212 taking the third attitude, there is a thirty-third space 133 as a part of the inner space 57. The thirty-third space 133 is partitioned by the sixth inner wall 506, the seventh inner wall 507, the upper outer wall 53, the front outer wall 51 and the rear outer wall 52, and below the lowermost position L7 of the surface of the seventh inner wall 507 defining the seventh communication hole 607.

The ink **60** stored in the twenty-eighth space **128** and the twenty-second space **122** of the ink tank **212** taking the second attitude shown in FIG. 21C is reserved in the twenty-seventh space **127** and the thirty-third space **133** of the ink tank **212** taking the third attitude shown in FIG. 21D.

When the ink tank **212** is further rotated leftward about the axis extending in the front-rear direction **8** so that the attitude of the ink tank **212** is changed from the third attitude to the usage attitude, the ink stored in the twenty-seventh space **127** and the thirty-third space **133** is stored in the thirty-second space **132**.

[Fourth, Fifth and Sixth Attitudes According to Twelfth Embodiment]

Referring to FIGS. 22A-22D, the ink tank **212** of which attitude is changed from the usage attitude to the sixth attitude through the fourth and fifth attitudes will be described. As shown in FIG. 22A, in a state where the ink tank **212** takes the usage attitude, the ink **60** is stored in the thirty-second space **132** of the ink tank **212** up to the full level line **L0**.

FIG. 22B shows the ink tank **212** taking the fourth attitude. The fourth attitude is defined as an attitude of the ink tank **212** when the ink tank **212** taking the usage attitude is rotated rightward (i.e., clockwise) about the axis extending in the front-rear direction **8** such that the rotation angle is larger than 0 degree to 90 degrees or less. The fourth attitude is the same as the third attitude described above referring to FIG. 21D. When the attitude of the ink tank **212** is changed from the usage attitude shown in FIG. 22A to the fourth attitude shown in FIG. 22B, the ink **60** stored in the thirty-second space **132** is reserved in the thirtieth space **130**.

FIG. 22C shows the ink tank **212** taking the fifth attitude. The fifth attitude is defined as an attitude of the ink tank **212** when the ink tank **212** taking the usage attitude is rotated rightward (i.e., clockwise) about the axis extending in the front-rear direction **8** such that the rotation angle is larger than 90 degrees to 180 degrees or less. The fifth attitude coincides with the second attitude described above referring to FIG. 21C. When the attitude of the ink tank **212** is changed from the fourth attitude shown in FIG. 22B to the fifth attitude shown in FIG. 22C, the ink **60** stored in the thirtieth space **130** is reserved in the twenty-eighth space **128**.

FIG. 22D shows the ink tank **212** taking the sixth attitude. The sixth attitude is defined as an attitude of the ink tank **212** when the ink tank **212** taking the usage attitude is rotated rightward (i.e., clockwise) about the axis extending in the front-rear direction **8** such that the rotation angle is larger than 180 degrees to 270 degrees or less. The sixth attitude coincides with the first attitude described above referring to FIG. 22B. When the attitude of the ink tank **212** is changed from the fifth attitude shown in FIG. 22C to the sixth attitude shown in FIG. 22D, the ink **60** stored in the twenty-eighth space **128** is reserved in the thirtieth space **130**.

When the ink tank **212** is further rotated rightward about the axis extending in the front-rear direction **8** so that the attitude of the ink tank **212** is changed from the sixth attitude to the usage attitude, the ink **60** stored in the thirtieth space **130** is reserved in the thirty-second space **132**.

Effects of Twelfth Embodiment

With the printer **10** according to the twelfth embodiment, when the ink tank **212** taking the usage attitude is rotated leftward about the axis extending in the front-rear direction **8** such that the rotation angle is larger than 0 degree to 90 degrees or less to take the first attitude, a part of the ink **60**

stored in the thirty-second space which is below the full level line **L0** of the ink tank **212** taking the usage attitude is stored in the thirtieth space **130**, while the remainder is stored in the thirty-first space **131**. When the attitude of the ink tank is changed from the first attitude to the second attitude as the ink tank **60** is rotated leftward such that the rotation angle is larger than 90 degree to 180 degrees or less, the ink **60** stored in the thirtieth space **130** is reserved in the twenty-eighth space **128**, and the ink **60** stored in the thirty-first space **131** is reserved in the twenty-second space **122**. When the attitude of the ink tank **212** is further changed from the second attitude to the third attitude as the ink tank **212** is rotated leftward such that the rotation angle is larger than 180 degree to 270 degrees or less, the ink **60** stored in the twenty-eighth space **128** is reserved in the twenty-seventh space **127**, and the ink **60** stored in the twenty-second space **122** is reserved in the thirty-third space **133**.

When the ink tank **212** is rotated rightward about the axis extending in the front-rear direction **8** such that the attitude of the ink tank **212** is changed from the usage attitude to anyone of the fourth attitude, fifth attitude and sixth attitude, the ink **60** stored in the thirty-second space **132** below the full level line **L0** in a state where the ink tank **212** takes the usage attitude is reserved in a space partitioned by the eighth inner wall **508**, the ninth inner wall **509**, the tenth inner wall **510** and the outer walls **51-56**.

Accordingly, even if the ink tank **212** is rotated about the axis extending in the front-rear direction **8** with the inlet being opened, the ink **60** stored in the inner space **57** hardly flows out.

[Ink Tank According to Thirteenth Embodiment]

Referring to FIGS. 23, 24A-24D and 25A-25D, an ink tank **213** according to a thirteenth embodiment will be described. The ink tank **213** according to the thirteenth embodiment is configured such that the eleventh inner wall **511**, the twelfth inner wall **512** and the thirteenth inner wall **513** are additionally provided to the ink tank **201** according to the twelfth embodiment. The other configuration of the thirteenth embodiment is the same as that of the twelfth embodiment and the detailed description will be omitted.

As shown in FIG. 23, the ink tank **213** has the eleventh inner wall **511**, the twelfth inner wall **512** and the thirteenth inner wall **513**.

When the ink tank **213** takes the usage attitude, the eleventh inner wall **511** is arranged below the tenth wall **510**, and extends rightward from the left outer wall **56**. The eleventh inner wall **511** partitions the twenty-ninth space **129** into a thirty-fourth space **134** on the upper side of the eleventh inner wall **511** and a thirty-fifth space **135** on the lower side of the eleventh inner wall **511**. The eleventh inner wall **511** has an eleventh communication hole **611** through which the thirty-fourth space **134** and the thirty-fifth space **135** communicate with each other.

When the ink tank **213** takes the usage attitude, the twelfth inner wall **512** extends downward from the eleventh inner wall **511** at a position on the left side with respect to the eleventh communication hole **611**. The twelfth inner wall **512** partitions the thirty-fifth space **135** into a thirty-sixth space **136** on the right side of the twelfth inner wall **512** and a thirty-seventh space **137** on the left side of the twelfth inner wall **512**. The twelfth inner wall **512** has a twelfth communication hole **612** through which the thirty-sixth space **136** and the thirty-seventh space **137** communicate with each other.

When the ink tank **213** takes the usage attitude, the thirteenth inner wall **513** extends leftward from the twelfth inner wall **512** at a position above the communication hole

612 of the twelfth inner wall. The thirteenth inner wall 513 partitions the thirty-seventh space 137 into a thirty-eighth space 138 on the upside of the thirteenth inner wall 513 and a thirty-ninth space 139 below the thirteenth inner wall 513. The thirteenth inner wall 513 has a thirteenth communication hole 613 through which the thirty-eighth space 138 and the thirty-ninth space 139 communicate with each other.

The ink tank 213 according to the thirteenth embodiment is configured such that two groups of inner walls 511-513, and one group of inner walls 508-510 are added in the twenty-ninth space 120 of the ink tank 212 according to the twelfth embodiment. Therefore, when the attitude of the ink tank 213 is changed from the usage attitude, through the first attitude and second attitude, to the third attitude as shown in FIGS. 24A-24D, and further changed to return the usage attitude, the ink 60 stored in the thirty-second space 132 of the ink tank 231 taking the usage attitude is reserved in the thirty-second space 132 without being spilt from the inlet 58. Similarly, as shown in FIGS. 25A-25D, when attitude of the ink tank 213 is changed from the usage attitude to the sixth attitude through the fourth attitude and the fifth attitude, and further changed to the usage attitude, the ink 60 stored in the thirty-second space 132 of the ink tank 231 taking the usage attitude is reserved in the thirty-second space 132 without being spilt from the inlet 58.

[Modifications]

According to the above-described embodiments, the ink tanks are described to have a rectangular parallelepiped shape. Such a shape is only an example, and the should not be limited to a particular shape but other shape could be employed. For example, the ink tank may have a cylindrical shape. For another example, the ink tank may have an inclined wall at an upper part thereof.

According to the above-described embodiments, the inlet 58 is provided to the upper outer wall 53. This configuration can be modified such that the inlet may be provided to an upper portion of one of the front outer wall 51, the rear outer wall 52, the right outer wall 55 and the left outer wall 56.

According to the above-described embodiments, the first communication hole 71 is located between the right end of the first inner wall 61 which extends rightward from the left outer wall 56 and the right outer wall 55, and the first communication hole 71 is located on the right side with respect to the first inner wall 61. The other inner walls 62-65 and 506-513, and other communication holes 72-75 and 606-613 have the similar relationship, respectively. It is noted that the first inner wall 61 may be configured to connect the left outer wall 56 and the right outer wall 57, and the first communication hole 71 may be formed at an intermediate position of the first inner wall 61. In such a case, a width of the first communication hole 71 in the front-rear direction 8 may be the same as a width of the first inner wall 61 so that the first inner wall 61 is divided into right and left portions. Alternatively, the width of the first communication hole 71 may be smaller than the width of the first inner wall 61 and the first communication hole 61 is formed as an opening formed on the first inner wall 61. The other inner walls 62-65 and 506-513 and the other communication holes 72-75 and 606-613 may be configured similarly.

According to the above-described embodiment, the first inner wall 61 has a rectangular shape when viewed from the up-down direction 7, and the first communication hole 71 also has a rectangular shape. The other communication holes 72-75 and 606-613 also have rectangular shapes. However, the shapes of the communication holes 72-75 and 606-613 need not be limited to the rectangular shapes, but can be

formed to have another polygonal shapes or circular shape. When the first communication hole 71 has a rectangular shape, surfaces that partition the first communication hole 71 are outer surfaces of a rectangular column having four planar surfaces, and one of the four planar surfaces is located at the lowermost position L1 of the surfaces partitioning the first communication hole 71. When the first communication hole 71 has a different shape, for example, a circular shape, the surface partitioning the first communication hole 71 is a circumferential surface of a cylinder, and a generating line of the cylinder is located at the lowermost position L1 of the surface partitioning the first communication hole 71.

In the above-described embodiments, each ink tank is formed with the full level line L0 on an outer wall. It is noted that the fourth space 104 need not be limited to a space defined by the full level line L0. That is, when the full level line L0 is not provided to an ink tank, the fourth space 104 may be defined as a space having half the capacity of the second space 102. In such a case, when the ink 60 corresponding to half the capacity of the second space 102 is stored in the ink tank, the ink 60 is prevented from spilling out from the inlet 58. If, for example, graduations in the up-down direction in the usage attitude are provided on the outer wall of the ink tank, a space below the uppermost graduation or the lowermost graduation may be defined as the fourth space 104.

When the inlet 58 is configured such that an air passage and an ink passage communicating with the second space 102 are formed in parallel, and a bottle filled with the ink 60 is connected to the inlet 58, and the ink 60 is supplied to the second space 102 in accordance with a so-called chicken-feed method, if a liquid level of the ink 60 in the second space 102 rises up to a lower end of the air passage, supplying of the ink 60 from the bottle to the second space 102 is ceased. When such a configuration is employed, the space below the lower end of the air passage is defined to be the fourth space 104.

The ink tank 208 according to the eighth embodiment described above has the first inner wall 61, the second inner wall 62, the third inner wall 63 and four fourth inner walls 64. It is noted that the ink tank 208 may be configured not to have the third inner wall.

What is claimed is:

1. A liquid consumption device, comprising:
a tank having an inner space partitioned, by an outer wall, from outside, an inlet through which the inner space communicates with the outside of the tank, and an outlet through which the inner space communicates with the outside of the tank;
a liquid consumption part connected to the outlet, wherein the tank has a first inner wall which extends, in a state where the tank takes a usage attitude, from the outer wall in one direction corresponding to a first direction perpendicular to an up-down direction, wherein the first inner wall partitions the inner space into a first space in which the inlet is located and a second space in which the outlet is located, the first inner wall unobstructedly facing the inlet and having a first communication hole through which the first space and second space communicate with each other, and wherein, a third space, which is partitioned by the first inner wall and the outer wall and is located below a lowermost position of a surface partitioning the first communication hole when the tank takes a first attitude which is defined as an attitude of the tank when the tank taking the usage attitude is rotated in another direction opposite to the one direction corresponding to the first

direction by an angle ranging from 0 degree to 90 degrees about a rotation axis extending in a second direction which is perpendicular to both the up-down direction and the first direction, is configured to store a particular amount of liquid, which is stored in a fourth space in a state where the tank takes the usage attitude, the fourth space being a part of the second space.

2. The liquid consumption device according to claim 1, wherein the tank comprises a second inner wall which extends downward, in a state where the tank takes the usage attitude, from the first inner wall at a position on a side, in the other direction, with respect to the first communication hole,

wherein the second inner wall partitions, in a state where the tank takes the first attitude, the second space into a fifth space on an upper side of the second inner wall and a sixth space on a lower side of the second inner wall, the second inner wall having a second communication hole through which the fifth space and the sixth space communicate with each other, and

wherein, a seventh space which is partitioned by the first inner wall, the second inner wall and the outer wall and located below the lowermost position of a surface, of the second inner wall, partitioning the second communication hole in a state where the tank takes a second attitude which is defined as an attitude of the tank when the tank is further rotated in the other direction by an angle ranging from 90 degrees to 180 degrees about the rotation axis is configured to store the liquid which is stored in the fourth space in a state where the tank takes the usage attitude.

3. The liquid consumption device according to claim 2, wherein the tank comprises a third inner wall which extends in the other direction from the second inner wall at a position above the second communication hole,

wherein the third inner wall partitions the sixth space into an eighth space and a ninth space, the eighth space being on the upper side and the ninth space being the lower side of the third inner wall in a state where the tank takes the usage attitude, the third inner wall having a third communication hole through which the eighth space and the ninth space communicate with each other, and

wherein a tenth space, which is partitioned by the first inner wall, the second inner wall, the third inner wall and the outer wall and located below a lowermost position of the surface, of the third inner wall, and partitions the third communication hole in a state where the tank takes a third attitude which is an attitude of the tank when rotated in the second direction by an angle ranging from 180 degrees to 270 degrees, is configured to store the liquid which is stored in the fourth space in a state where the tank takes the usage attitude.

4. The liquid consumption device according to claim 1, wherein, in a state where the liquid consumption device takes the usage attitude, the first inner wall has an upper surface tilted downward toward the one direction from the outer wall.

5. The liquid consumption device according to claim 2, wherein, in a state where the liquid consumption device takes the usage attitude, the second inner wall has a side surface facing the one direction, the side surface tilted in the other direction toward a lower direction which is a lower direction in a state where the liquid consumption device takes the usage attitude.

6. The liquid consumption device according to claim 3, wherein the third inner wall has a lower surface which is tilted upward toward the other direction, the upward direction being an upward direction in a state where the liquid consumption device takes the usage attitude.

7. The liquid consumption device according to claim 3, wherein the third inner wall has an upper surface, which is an upper surface of the third inner wall in a state where the liquid consumption device takes the usage attitude, tilted downward toward the other direction.

8. The liquid consumption device according to claim 1, wherein, in a state where the tank takes a fourth attitude which is defined as an attitude of the tank when the tank taking the usage attitude is rotated by an angle ranging from 0 degree to 90 degrees in the one direction about the rotation axis, the liquid stored in the fourth space in a state where the tank takes the usage attitude can be stored in an eleventh space which is a part of the inner space partitioned by the outer wall and defined as a space on the lower side with respect to the inlet in a state where the tank takes a fourth attitude.

9. The liquid consumption device according to claim 3, wherein the tank further comprises a fourth inner wall extending, from the second inner wall, in the other direction, the fourth inner wall being arranged, when the tank takes the usage attitude, on a lower side with respect to the first inner wall and on an upper side with respect to the third inner wall, and

wherein the fourth inner wall partitions the ninth space into a space on an upper side, in a state where the tank takes the usage attitude, with respect to the fourth inner wall and a space on a lower side with respect to the fourth inner wall, a fourth communication hole being formed on the fourth inner wall through which the space on the upper side and the space on the lower side with respect to the fourth inner wall communicating with each other.

10. The liquid consumption device according to claim 3, further having a fifth inner wall extending in a lower direction, which is a lower direction in a state where the tank takes the usage attitude, from the outer wall, wherein the fifth inner wall partitions the first space into a twelfth space in which the inlet is located and a thirteenth space located on the one direction side, in the state where the tank takes the usage attitude, with respect to the twelfth space, the fifth inner wall having a fifth communication hole through which the twelfth space and the thirteenth space communicate with each other, and

wherein, a fourteenth space, which is partitioned by fifth inner wall and the outer wall, and located below a lowermost position of a surface of the fifth inner wall defining the fifth communication hole in a state where the tank takes a fifth attitude which is an attitude when the tank taking the usage attitude is rotated in the one direction by an angle ranging from 90 degrees to 180 degrees about the rotation axis, is configured to store all the amount of liquid flows from the fourth space to the fourteenth space via the fifth space when the tank is rotated in the one direction, about the rotation axis, from the usage attitude to the fifth attitude.

11. The liquid consumption device according to claim 10, wherein, in a state where the tank takes the usage attitude, at least a lower part of the fifth inner wall is tilted in the one direction toward a lower end thereof, wherein, in a state where the tank takes a sixth attitude which is an attitude of the tank when the tank taking the

usage attitude is rotated by an angle ranging from 180 degrees to 270 degrees in the second direction, a fifteenth space, which is partitioned by the fifth inner wall and the outer wall and defined below a lowermost position of a surface of the fifth inner wall partitioning the fifth communication hole, can store the liquid which is stored in the fourteenth space in a state where the tank takes the fifth attitude.

12. The liquid consumption device according to claim 1, wherein a full level line is indicated on the outer wall, the full level line being indicated on a lower side with respect to the first inner wall and representing a maximum amount of the liquid storable in the second space in the state where the tank takes the usage attitude, the amount of the liquid being the liquid stored in the second space below the full level line.

13. A liquid consumption device, comprising:

a tank having an inner space partitioned, by outer wall, from outside, an inlet through which the inner space communicates with the outside of the tank, and outlet through which the inner space communicates with the outside of the tank;

a liquid consumption part connected to the outlet, wherein the tank comprises, in a state where the tank takes a usage attitude:

a sixth inner wall extending, from the outer wall, in one direction corresponding to a first direction perpendicular to an up-down direction, the sixth inner wall partitioning the inner space into a twentieth space in which the inlet is included and a twenty-first space in which the outlet is included, the sixth inner wall being formed with a sixth communication hole through which the twentieth space and the twenty-first space communicate with each other;

a seventh inner wall extending in another direction opposite to the one direction corresponding to the first direction from a portion which is a part of the sixth inner wall and on the other direction side with respect to the sixth communication hole, the seventh inner wall partitioning the twenty-first space into a twenty-second space on an upper side and a twenty-third space on a lower side with respect to the seventh inner wall, the seventh inner wall being formed with a seventh communication hole through which the twenty-second space and the twenty-third space communicate with each other;

an eighth inner wall arranged on a lower side of the seventh inner wall and extending from the outer wall in the other direction, the eighth inner wall partitioning the twenty-third space into a twenty-fourth space on an upper side and a twenty-fifth space on a lower side with respect to the eighth inner wall, the eighth inner wall being formed with an eighth communication hole through which the twenty-fourth space and the twenty-fifth space communicate with each other;

a ninth inner wall extending downward from the eighth inner wall at a position on the one direction side with respect to the eighth communication hole, the ninth inner wall partitioning the twenty-fifth space into a twenty-sixth space on the other direction side and a twenty-seventh space on the one direction side with respect to the ninth inner wall, the ninth inner wall being formed with a ninth communication hole through which the twenty-sixth space and the twenty-seventh space communicate with each other; and

a tenth inner wall extending in the one direction from the ninth inner wall at a position on an upper side with

respect to the ninth communication hole, the tenth inner wall partitioning the twenty-seventh space into an twenty-eighth space on an upper side and a twenty-ninth space on a lower side with respect to the tenth inner wall, the tenth inner wall being formed with a tenth communication hole through which the twenty-eighth space and the twenty-ninth space communicate with each other,

wherein, in a state where the tank takes the usage attitude, a full level line is indicated on the outer wall, the full level line representing a maximum amount of the liquid storable in the twenty-fifth space and below the eighth inner wall,

wherein, in a state where the tank takes a first attitude which is an attitude of the tank when the tank taking the usage attitude is rotated by an angle ranging from 0 degrees to 90 degrees in the other direction about an axis extending in a second direction, a thirtieth space and a thirty-first space are capable of storing the liquid which is stored in a thirty-second space below the full level line in the state where the tank takes the usage attitude, the thirtieth space being a space partitioned by the eighth inner wall, the ninth inner wall, the tenth inner wall and the outer wall and located on a lower side with respect to a lowermost position of a surface of the tenth inner wall defining the tenth communication hole, and a thirty-first space being a space partitioned by the seventh inner wall and the outer wall and a part lower than a lowermost position of a surface of the seventh inner wall defining the seventh communication hole,

wherein, in a state where the tank takes a second attitude which is an attitude of the tank when the tank taking the usage attitude is rotated in the other direction by 180 degrees about the axis extending in the second direction, the twenty-eighth space and the twenty-second space are capable of storing the liquid which is stored in the thirty-second space in the state where the tank takes the usage attitude, and

wherein, in a state where the tank takes a third attitude which is an attitude of the tank when the tank taking the usage attitude is rotated in the other direction by an angle ranging from 180 degrees to 270 degrees about the axis extending in the second direction, the twenty-seventh space and a thirty-third space are capable of storing the liquid stored in the thirty-second space in a state where the tank takes the usage attitude, the thirty-third space being a space defined by the sixth inner wall, the seventh inner wall and the outer wall and located on the lower side with respect to a lowermost position of a surface of the seventh inner wall defining the seventh communication hole.

14. The liquid consumption device according to claim 13, wherein the tank further comprises an eleventh inner wall, a twelfth inner wall and a thirteenth inner wall, the eleventh inner wall being a wall located on a lower side with respect to the tenth inner wall and extending in the one direction from the outer wall, the eleventh inner wall partitioning the twenty-ninth space into a thirty-fourth space on an upper side and a thirty-fifth space on a lower side with respect to the eleventh inner wall, the eleventh inner wall being formed with an eleventh communication hole through which the thirty-fourth space and the thirty-fifth space communicate with each other; the twelfth inner wall being a wall extending downward from the eleventh inner wall at a position on the other

31

direction side with respect to the eleventh communication hole, the twelfth inner wall partitioning the thirty-fifth space into a thirty-sixth space on the one direction side and a thirty-seventh space on the other direction side with respect to the twelfth inner wall, the twelfth inner wall being formed with a twelfth communication hole through which the thirty-sixth space and the thirty-seventh space communicate with each other; and

the thirteenth inner wall being a wall extending in the other direction from the twelfth inner wall at a position on an upper side with respect to the twelfth communication hole, the thirteenth inner wall partitioning the thirty-seventh space into a thirty-eighth space on an upper side and a thirty-ninth space on a lower side with respect to the thirteenth inner wall, the thirteenth inner wall being formed with a thirteenth communication hole through which the thirty-eighth space and the thirty-ninth space communicate with each other.

15. The liquid consumption device according to claim 14, wherein the eighth inner wall, the ninth inner wall and the tenth inner wall are arranged on an upper side with respect to the eleventh inner wall and on a lower side with respect to the thirteenth inner wall in the state where the tank takes the usage attitude.

16. A liquid tank for a liquid consumption device, comprising:

an outer wall defining an inner space of the tank, the inner space being partitioned from an outside by the outer wall;

an inlet through which the inner space communicates with the outside of the tank; and

an outlet to which the liquid consumption device is connectable such that the inner space of the tank can communicate with the liquid consumption device; a first inner wall which extends, in a state where the tank takes a usage attitude, from the outer wall in one direction in-corresponding to a first direction perpendicular to an up-down direction,

wherein the first inner wall partitions the inner space into a first space in which the inlet is located and a second space in which the outlet is located, the first inner wall unobstructedly facing the inlet and having a first communication hole through which the first space and second space communicate with each other, and

wherein, a third space, which is partitioned by the first inner wall and the outer wall and is located below a lowermost position of a surface partitioning the first communication hole in a state where the tank takes a first attitude which is defined as an attitude in a state the tank taking the usage attitude is rotated in another direction opposite to the one direction corresponding to the first direction by an angle ranging from 0 degree to 90 degrees about a rotation axis extending in a second direction which is perpendicular to both the up-down direction and the first direction, is configured to store a particular amount of liquid, which is stored in a fourth space in a state where the tank takes the usage attitude, the fourth space being a part of the second space.

17. A liquid consumption device, comprising: a tank having an inner space partitioned, by an outer wall, from outside, an inlet through which the inner space communicates with the outside of the tank, and an outlet through which the inner space communicates with the outside of the tank;

32

a liquid consumption part connected to the outlet, wherein the tank has a first inner wall which extends, in a state where the tank takes a usage attitude, from the outer wall on one side in a first direction perpendicular to an up-down direction,

wherein the first inner wall partitions the inner space into a first space in which the inlet is located and a second space in which the outlet is located, the first inner wall having a first communication hole through which the first space and second space communicate with each other, and

wherein, a third space, which is partitioned by the first inner wall and the outer wall and is located below a lowermost position of a surface partitioning the first communication hole when the tank takes a first attitude which is defined as an attitude of the tank when the tank taking the usage attitude is rotated on another side in the first direction by an angle ranging from 0 degree to 90 degrees about a rotation axis extending in a second direction which is perpendicular to both the up-down direction and the first direction, is configured to store a particular amount of liquid, which is stored in a fourth space in a state where the tank takes the usage attitude, the fourth space being a part of the second space,

wherein the tank comprises a second inner wall which extends downward, in a state where the tank takes the usage attitude, from the first inner wall at a position on the other side of the first direction with respect to the first communication hole,

wherein the second inner wall partitions, in a state where the tank takes the first attitude, the second space into a fifth space on an upper side of the second inner wall and a sixth space on the lower side of the second inner wall, the second inner wall having a second communication hole through which the fifth space and the sixth space communicate with each other, and

wherein, a seventh space which is partitioned by the first inner wall, the second inner wall and the outer wall and located below the lowermost position of a surface, of the second inner wall, partitioning the second communication hole in a state where the tank takes a second attitude which is defined as an attitude of the tank when the tank is further rotated in the other direction by an angle ranging from 90 degrees to 180 degrees about the rotation axis is configured to store the liquid which is stored in the fourth space in a state where the tank takes the usage attitude.

18. A liquid tank for a liquid consumption device, comprising:

an outer wall defining an inner space of the tank, the inner space being partitioned from an outside by the outer wall;

an inlet through which the inner space communicates with the outside of the tank; and

an outlet to which the liquid consumption device is connectable such that the inner space of the tank can communicate with the liquid consumption device;

a first inner wall which extends, in a state where the tank takes a usage attitude, from the outer wall on a one side in a first direction perpendicular to an up-down direction,

wherein the first inner wall partitions the inner space into a first space in which the inlet is located and a second space in which the outlet is located, the first inner wall having a first communication hole through which the first space and second space communicate with each other, and

33

wherein, a third space, which is partitioned by the first inner wall and the outer wall and is located below a lowermost position of a surface partitioning the first communication hole in a state where the tank takes a first attitude which is defined as an attitude in a state the tank taking the usage attitude is rotated on another side in the first direction by an angle ranging from 0 degree to 90 degrees about a rotation axis extending in a second direction which is perpendicular to both the up-down direction and the first direction, is configured to store a particular amount of liquid, which is stored in a fourth space in a state where the tank takes the usage attitude, the fourth space being a part of the second space,
 wherein the tank comprises a second inner wall which extends downward, in a state where the tank takes the usage attitude, from the first inner wall at a position on the other side of the first direction with respect to the first communication hole,
 15

5

34

wherein the second inner wall partitions, in a state where the tank takes the first attitude, the second space into a fifth space on an upper side of the second inner wall and a sixth space on the lower side of the second inner wall, the second wall having a second communication hole through which the fifth space and the sixth space communicate with each other, and
 wherein, a seventh space which is partitioned by the first inner wall, the second inner wall and the outer wall and located below the lowermost position of a surface, of the second inner wall, partitioning the second communication hole in a state where the tank takes a second attitude which is defined as an attitude of the tank when the tank is further rotated in the other direction by an angle ranging from 90 degrees to 180 degrees about the rotation axis is configured to store the liquid which is stored in the fourth space in a state where the tank takes the usage attitude.
